CHIMNEY HOPPER FOR INCINERATORS

Filed Sept. 14, 1927

UNITED STATES PATENT OFFICE

ROBERT T. WYSE, OF PITTSBURGH, PENNSYLVANIA

CHIMNEY HOPPER FOR INCINERATORS

Application filed September 14, 1927. Serial No. 219,444.

The primary object of this invention is to provide a hopper for general use, but particularly for receiving and discharging garbage and other refuse into a chimney flue for incineration in the basement of an apartment house.

A second object is to provide such a device which will catapult the garbage or refuse into the chimney flue without depending upon the 10 degree of inclination to cause gravitation of the same into the chimney flue.

A third object is to avoid the presence of pockets in which burning embers, soot and the like may accumulate to later be forced into 15 the room by the draft caused by the opening of the hopper door for the deposit of refuse, this being avoided by the provision of a closure substantially flush with the inner face of the chimney flue, thereby also avoiding the 20 presence of air pockets to reduce the draft.

A further object is to provide a hopper with means whereby leakage of smoke, fumes and the like into the room will be avoided by quick 25 acting automatic closing of the opening into the chimney flue when the hopper is in its open or closed position.

A still further object is to avoid the presence of projections into the chimney flue to interfere with and reduce the draft.

With these and other important objects in 30 view, reference will be had to the accompanying drawing which forms a part of this specification and in which—

Fig. 1 is a vertical sectional view of a chimney wall with the hopper applied and in closed position,

Fig. 2 is a similar view with the parts in open position,

Fig. 3 is a rear elevation view of Fig. 1, and

Fig. 4 is a front elevation view of Fig. 2.

Referring to the drawing, reference numeral 2 indicates a chimney wall in which is built a metal flue-box comprising a horizontal top wall 3, parallel vertical side walls 4 at 45 right angles to the wall 3, and downwardly and rearwardly sloping bottom wall 5. For convenience in installing the hopper in place, a foot 6 is provided on the lower outer side of the bottom wall 5. The back of the flue-box 50 is open, except for a depending flange or back

plate 7, alinged with which is a flange 8 to aid in anchoring the flue-box in the wall. The walls 3, 4 and 5 terminate substantially in the plane of the front face of the wall 2 and receive the door frame, which consists of a rectangular plate 9, provided with a charging opening 10 surrounded by a rim 11. This rim is beveled upwardly and rearwardly and is closed by an inclined door 12 having a marginal flange 14 which engages over the said rim 11 of the door frame plate 9. The door frame plate 9 is mounted in place, after the plastering is applied to the wall 2, by screws 15 which pass through said plate 9 into threaded ears 16 provided on the side walls 4 of the flue-box. The door 12 is provided with perforated ears 17 which are pivoted by pintle means 18 to ears 19 provided on the outer side of the bottom wall of the rim 11, a handle 20 being provided for opening and closing the door 12.

The inner side of the door 12 is provided with a joint closing plate or flange 21 which engages the upper outer edges of the lower wall of the rim 12 when the door is opened to prevent smoke, odors and the like from passing through this joint into the room. A pair of parallel side walls 22 are attached to the inner face of the door 12 and ends of the plate or flange 21 and extend inwardly a considerable distance, hugging the side walls 4 of the flue-box closely to prevent leakage of smoke, odors and the like into the room. The rear free ends of the walls 22 are bridged by a bar 24 and held thereby against displacement, and upon this bar 24 is hingedly mounted the hopper scoop bottom plate 25. This plate 25 is bowed so as to form a cupped garbage receiving element when the door is opened, at which time, the forward edge 26 engages the inner face of the door 12, while the opposite end 27 engages the lower edge of the flange 7 preventing, with the other parts described, the passage of smoke and odors into the room.

Adjacent its side edges, the hopper scoop bottom plate 25 is provided on its under side (open position) with rocker flanges 30, which, when the door is moved toward closing position, will move downwardly into engagement

with the inclined wall 5 and cause the hopper scoop bottom plate 25 to swing to the position in Fig. 1 with its edge 26 engaged with the inner face of the flange 7, causing the garbage that was deposited on said plate 25 to be automatically dumped into the chimney, falling down the same to the incinerating grate, not shown, but in common use.

It will be understood that in apartment houses where one or more hoppers are installed for each floor, that any leakage through the joints of the hopper will be multiplied by the number of hoppers on that floor plus the hoppers on the other floors, so that however small the leakage might be at any one hopper, when multiplied by the total number of hoppers, the total leakage may be considerable and so great as to cause material draft trouble. To avoid such leakage and to reduce the same to a minimum, this invention is provided, and it will be seen that when the door 12 is opened for the deposit of garbage, that the movement of the pintle bar 24 upwardly will cause the hopper scoop bottom plate 25 to quickly fall to its receiving position (Fig. 2) and directly thereafter, the end 27 engages the flange 7 and with the other parts closes the opening into the flue. Then, upon closing the door, the rocker engaging the bottom 5 as aforementioned, causes the hopper scoop bottom plate 25 to swing to its vertical (Fig. 1) position, catapulting the garbage into the chimney flue, and preventing the adherence of any of the garbage to such plate. When in its vertical position, the opening into the chimney flue is closed not only thereby, but further sealing is effected by the door 12 being closed. This not only gives protection against the annoyance of smoke and objectionable fumes entering the room, but gives assurance against the accumulation of burning embers lodging in the usual hopper pockets and later entering the room, this in itself being a great fire protection.

45. What is claimed:—

1. The combination with a flue, of a hopper having relatively movable members for automatically positively closing the passage into the flue when the hopper is in its full open and closed positions, and means for moving one of said members relatively to the other for catapulting the hopper contents into the flue.
55. 2. A device of the character described, comprising a housing having spaced walls, and a receiving member pivoted in said housing and including relatively movable front and rear members, the front member being adapted to engage one of said walls in closed position and the opposite end of the rear member being adapted to engage the other of said walls in open or closed position.
65. 3. A device of the character described, comprising a housing having spaced front and

70. rear walls, a receiving member pivoted in said housing and having a portion engageable with the front wall only in the closed position and having another portion the opposite ends of which are engageable with the rear wall in both closed and open positions of the receiving member.

4. In a device of the character described, a housing, a door hinged to the front side thereof, and a bottom member carried by said door and automatically movable upon opening movement of said door into engagement with said door and a rear portion of said housing, and automatically movable upon closing movement of said door into engagement with a rear portion of said housing.

5. In a device of the character described, a housing, a door pivotally mounted thereon, a bottom member carried by said door and movable relatively to the latter, and means for automatically moving said member relatively to the door and for catapulting the contents of said member therefrom upon swinging said door to closed position.

6. In a device of the character described, a housing member provided with a through passage, a door for said passage pivotally mounted on the housing, a receiving member carried by the door and having a movable bottom, and means on one of said members engageable with the other for automatically moving the bottom relatively to the receiving member to catapult its contents therefrom.

7. In a device of the character described, a housing member provided with a through passage, a door for said passage, a receiving member pivotally carried by the door and adapted to move by gravity into engagement with the door upon opening of the door, and means on one of said members engageable with the other for giving the receiving member and contents catapulting movement and for moving the receiving member into passage closing position upon closing of the door.

8. In a device of the character described, a housing member provided with a through passageway having front and rear walls, a door pivotally mounted on said front wall for closing the passageway and having rigidly connected wings extending downwardly and inwardly into the passageway, a bottom having its lower edge pivotally connected to the lower ends of the wings, and means for forcing the upper end of the bottom into contact with said rear wall when the door is in closed position.

9. In a device of the character described, a housing member provided with a through passageway and having front and rear walls, a door pivotally connected at its lower portion to said front wall, wings rigidly connected to the door and extending downwardly into the passageway, a bottom having its lower edge pivotally connected to the lower

ends of the wings, the upper end of the bottom engaging said rear wall when the door is in closed position, and means for moving the upper portion of the bottom into contact with the door when the latter is moved to open position.

10. In a device of the character described, a housing having a passageway therethrough, provided with front, rear and lower inclined walls, a door having its lower portion pivotally mounted on the upper portion of said front wall, wings rigidly connected to the door and extending downwardly into the passageway, a bottom having its lower edge pivotally connected to the lower ends of the wings, means at the lower end of the bottom to engage said inclined wall and move the upper edge of the bottom into contact with said rear wall, the bottom being movable into contact with the door when the latter is moved to open position.

In testimony whereof I affix my signature.
ROBERT T. WYSE.
